CLAIM

The ornamental design for a USB flash drive, as shown and described.

DESCRIPTION

FIG. 1 is a bottom exploded perspective view of a USB flash drive.

FIG. 2 is a bottom perspective of the USB flash drive in an extracted position from its carrier.

FIG. 3 is a bottom perspective view of the USB flash drive in an extracted position from its carrier, showing the top perspective view of the carrier.

FIG. 4 is a bottom perspective view of the USB flash drive in an inserted position into its carrier, showing the top perspective view of the carrier.

FIG. 5 is a bottom perspective view of the USB flash drive in an inserted position into its carrier.

FIG. 6 is a top exploded perspective view of the USB flash drive, showing the bottom perspective view of the carrier.

FIG. 7 is a top perspective view of the USB flash drive in an extracted position from its carrier, showing the bottom perspective view of the carrier.

FIG. 8 is a top perspective view of the USB flash drive in an extracted position from its carrier.

FIG. 9 is a top perspective view of the USB flash drive in an inserted position into its carrier; and,

FIG. 10 is a top perspective view of the USB flash drive in an inserted position into its carrier, showing the bottom perspective view of the carrier.

The broken line showing is included for the purpose of illustrating environmental structure and forms no part of the claimed design.
